G. D. NICHOLSON

BY

John Justice

ATTORNEY.

UNITED STATES PATENT OFFICE

GEORGE D. NICHOLSON, OF CAMBRIDGE, OHIO

AIR HEATER

Application filed June 4, 1928. Serial No. 282,794.

This invention relates to improvements in air heaters.

The prime object of the invention is to provide a unit for utilizing waste heat ordinarily allowed to pass off through the flue to the atmosphere.

A further object of the invention is to provide a specific form of radiator unit for the passage of the escaping products of combustion and spent gases, whereby to afford ample surface to collect the heat and dissipate the same to heat air introduced around the radiator for subsequent use.

A still further object of the invention is to provide a radiator with a circuitous path for the escaping products of combustion, and surround the radiator with a casing to trap air and heat same to be subsequently utilized for heating purposes.

The invention also comprehends improvements in the details of construction and arrangement of parts which will be hereinafter described and particularly pointed out in the claims.

In the drawing:

Fig. 1 is a top plan view of my improved heater.

Fig. 2 is a side elevation of the same.

Fig. 3 is an end view.

1 indicates a radiator or manifold comprising a series of superimposed flat sections 2, connected at opposite ends with adjacent sections by short pipe sections 3. The upper flat section is extended at one end beyond the vertical plane of the sections below, the extension having an opening 4 with which an inlet flue 5 communicates.

At the ends of the flat sections adjacent to the ends connected by the short pipe sections 3, are interposed plates which form supports or braces between the sections. The lowermost flat section 2 is connected to an exit flue 6.

Fitting over the radiator section and spaced from the same, is a casing 7. This casing is supported on legs and is open at the bottom for free admission of air in the space around the radiator. An outlet opening or openings 9, is formed in the upper portion of the casing for the exit of the heated air, and

between the end of the top flat section 2 is a baffle 10, which deflects the rising air toward the opening 9.

In operation, the improved heater is disposed adjacent a gas or coal heater or furnace using any form of fuel, the flue pipe being connected to the inlet flue 5. The escaping products of combustion then pass into the topmost flat section 1, thence through the topmost short pipe section 3 to the next adjacent flat section. The products pass lengthwise through the next flat section and out the short pipe section and so on throughout the length of the radiator to the exit flue 6. In transit, the escaping products of combustion and spent gases follow a zig-zag course and by the time the exit flue 6 is reached, substantially all the heat has been given off. The heat passing through the radiator heats the air passing through the bottom of the casing, and this highly heated air is conveyed through pipes to rooms or other places desired.

Obviously, the arrangement of the radiator sections is such as to afford the greatest amount of heating surface in a small space, and that the construction will effectually heat the air and thereby utilize the heat which would otherwise be wasted.

An important feature of the construction is the flue from the heating appliances located adjacent the end of the radiator, in that this arrangement tends to heat the radiator and thereby prolong the heat in the products of combustion passing to the exit flue.

To support the radiator, braces 15 are interposed between the flat sections, while bars or the like 16 at the bottom of the casing afford a support for the lowermost section.

It is thought from the foregoing description the construction will be readily understood and the advantages fully appreciated.

What I claim is:

1. A radiator including a casing open at the bottom and closed at the top, one wall of the casing near the top being formed with an outlet opening, a heating element arranged in the casing and including a series of superimposed hollow sections interconnected at relatively opposite ends to provide a tortuous

passage throughout the heating element, said heating element being arranged within the casing in spaced relation to the walls thereof, the upper section of the heating element being 5 extended beyond the remaining sections, and a flue pipe connected to the extended portion of said upper section, said flue pipe extending longitudinally of and wholly beyond the heating element and within and spaced from 10 the casing for a length corresponding to the vertical dimension of the heating element, whereby the air within the casing is heated by the heating element and by the flue pipe.

2. A radiator comprising a casing open 15 at the bottom and closed at the top and having side and end walls, one of the side walls being formed near the top of the casing with a heated air outlet, a heating element arranged wholly within the casing and comprising a series of superimposed hollow sections connected for intercommunication, the uppermost section being extended laterally, said heating element being arranged in the casing in spaced relation to the side walls and 25 substantially to one side of the vertical median line of the casing, to thereby provide a materially larger casing space beyond the heating element in one direction than in the opposite direction, and a flue pipe projecting 30 within the enlarged space in the casing and extended parallel to the heating element and connected to and in open communication with the projecting portion of the uppermost section of the heating element.

3. In testimony whereof I affix my signature.
GEORGE D. NICHOLSON. [L.S.]
